United States Patent Office.

LAWRENCE B. WATERMAN, OF INDIANAPOLIS, INDIANA, ASSIGNOR TO
JOHN CARLON AND COMPANY.

Letters Patent No. 75,499, dated March 10, 1868.

IMPROVEMENT IN INKING-APPARATUS FOR COLOR-PRINTING.

The Schedule referred to in these Letters Patent and making part of the same.

Be it known that I, LAWRENCE B. WATERMAN, of Indianapolis, Marion county, Indiana, have invented a new and useful Improvement in Inking-Attachment for Printing-Presses for Printing in Colors; and I do hereby declare that the following is a clear, full, and exact description of the construction and operation of the same, reference being had to the annexed drawings, making part of this specification, in which—

Figure 1 is a side longitudinal elevation.

Figure 2 is an end sectional view.

Figures 3, 4, and 5, are sectional parts of the same.

Figure 6 is a longitudinal section of the inking-roller and its removable shaft.

This invention has reference to that class of machines known as inking-attachments or inking-apparatuses for printing-presses, by which one or more colors are produced by one impression.

My improvement consists chiefly as follows: Constructing the plates *c c c* of any thin metal plate, or of wood, in form of a segment of a circle, slotted at its centre to receive the screw-rod *D*, and it will be seen that thick or thin lines can be formed; these lines being used to transfer the ink from the ink-receiving rollers *I J* to the type-rollers used on the press, bands being formed on the type-rollers of different colors, in numbers according to the number of sets of plates *c c c* and ink-receiving rollers *I J* used. But one set of rollers *I J* and one set of plates are shown in the accompanying drawing, but additional sets may be attached to the cylinder *B*, when more colors are produced. I am aware that solid lines could be used to produce the same effect that I make with my plates *c c c*, but by the use of the plates *c c c*, any thickness of line can be formed with little trouble, and the necessity obviated of making that number of solid lines required to produce the same result. It will be seen that lines must be formed the sizes or thickness of all kinds of type made or used, hence the universal adaptation of the plates *c c c* to produce that result. The cylinder *B* is made of iron, being turned true and smooth, and is provided with raised flanges at either end, for the purpose of securing the screw-rod *L*, on to which the plates *c c c* are attached, the screw-rod *D* being provided with a thread its entire length, so that the lines may be adjusted at any point thereon, separately and firmly secured to said rod *D*, by means of the nuts *e e*. The motion of the ink-receiving rollers *I* and *J*, necessary for the distribution of the ink, and also for throwing on and off the cylinder or plates *c c c* at a proper point, is derived from the motion of the cylinder *B*. The rotary motion necessary for the distribution of the ink is driven by the pulleys *P* and *L*, by means of a belt. The sliding or reciprocating motion of the rollers *I* and *J* on and off the plates *c c c*, is produced by the sliding box *H* coming in contact with the cam *G*, which is attached to either ends of the cylinder *B*, on its journals or bearings, all of which is produced with certainty and cheapness, and with little resistance to the cylinder *B*. To facilitate the attaching and detaching of the roller *I* in order to wash it, (it being a soft composition roller,) independent of the roller *J*, which is made of wood, and does not require to be removed for the purpose of washing or otherwise preparing for work, I provide the soft roller *I* with a hollow core, *y*, and insert the rod *K* its entire length, as shown in fig. 1; the rod *K* extending through the core *y* at either end, which forms a journal or bearing to turn upon, which I regard as being very useful and labor-saving, obviating the necessity of removing the hard roller *J*, and the boxes and appurtenances belonging thereto.

I believe I have invented some useful, cheap, and labor-saving improvements in inking-machines, which I have herein described, which I claim as my invention, and desire to secure by Letters Patent. I do not claim sector-plates as new with me, but

What I do claim, and desire to secure by Letters Patent, is—

1. The screw-rod *D* and nuts *e e*, in combination with sectional plates *c c c*, having slots *c' c'*, all combined and arranged substantially as and for the purpose set forth.
2. The inking-roller *I*, provided with the removable shaft *K*, working in a sliding bearing *H*, in combination with the distributing-roller *J*, having fixed bearings *J'*, substantially as and for the purpose set forth.

L. B. WATERMAN.
